US0D1017153S

(12) **United States Design Patent** (10) **Patent No.:** **US D1,017,153 S**
Kuckuck et al. (45) **Date of Patent:** **** Mar. 5, 2024**

(54) **BLOWER**

(71) Applicants: **Randy Leon Kuckuck**, Dundee, MI (US); **Kevin Lee Newcomer**, Monroe, MI (US)

(72) Inventors: **Randy Leon Kuckuck**, Dundee, MI (US); **Kevin Lee Newcomer**, Monroe, MI (US)

(**) Term: **15 Years**

(21) Appl. No.: **29/796,448**

(22) Filed: **Jun. 24, 2021**

Related U.S. Application Data

(63) Continuation of application No. 17/220,351, filed on Apr. 1, 2021, which is a continuation of application No. 16/398,311, filed on Apr. 30, 2019, now Pat. No. 10,966,378.

(57) **CLAIM**

We claim the ornamental design for a blower, as shown and described.

DESCRIPTION

FIG. 1 is a bottom-front perspective view of an example blower showing our design.

FIG. 2 is a bottom view of the blower illustrated in FIG. 1.

FIG. 3 is a top view of the blower illustrated in FIG. 1.

FIG. 4 is a left side view of the blower illustrated in FIG. 1; and,

FIG. 5 is a rear view of the blower illustrated in FIG. 1. The right side view of the blower is a mirror image of the left side view of the blower.

The broken lines in the figures are for illustrative purposes only and form no part of the claimed design.

1 Claim, 2 Drawing Sheets
